TAPE DRAWING DEVICE

August D. Eitzen, Rockville Centre, N. Y., assignor to News Projection Corporation, New York, N. Y., a corporation of New York

Application May 28, 1935, Serial No. 23,819

12 Claims. (Cl. 271—2.3)

This invention relates to tape drawing devices for telegraphic printers in general and more especially to tape drawing devices for telegraphic printers associated with a support usable as an inspection area or scanning area for a projector or a scanning device for television apparatus or the like and constitutes in part a continuation of my copending application for patent, Serial No. 329,026 filed December 28, 1928.

325,026 filed December 11, 1986

10 Among the objects of the present invention, it is aimed to provide an improved tape drawing device for a telegraphic printer especially when associated with a support usable as an inspection area for a projector or a scanning area for a scanning device of a television apparatus or the like.

15

15 It is another object of the present invention to provide an improved tape drawing device for a telegraphic printer having a tape puller and a continuously operating electric motor operatively associated normally to rotate said tape puller and yet responsive to the increased tension in the tape resulting when the tape puller continues to operate after the printer comes to rest in turn to actuate a restraining member to lock the tape puller against further movement.

25 These and other features, capabilities and advantages of the invention will appear from the subjoined detail description of specific embodiments thereof illustrated in the accompanying drawings in which—

30 drawings in which:

Figure 1 is a diagrammatic view of the several essential parts constituting the present invention showing the ticker and projector in front elevation and the tape puller in plan;

35 Fig. 2 is a diagrammatic view showing the several parts of the invention with the tape puller as well as the ticker and projector in side elevation and as a result the path followed by the tape from the projector to the tape puller.

40 Fig. 3 is a front elevation of the control for the tape puller separated from the motor and driving connection; and

Fig. 4 is a front elevation of an assembly showing another embodiment of the present invention.

45 In the embodiment shown in Figs. 1, 2 and 3, the tape 1 passes from the ticker 2 under the finger 3 and then over the idler 4 at the entrance end of the support constituting the light aperture of the projector 5 and then across the idler 6 at 50 the discharge end of the support and from there down to the tape pulling roller 7 rotatably mounted on the shaft 8 journaled in the casing 9. From the roller 7, the tape 1 then passes onto a suitable rewind reel 10, and further to a film magazine 11.

56 The finger 3 in the present embodiment is con-

connected to the upper end of the link 11 pivotally connected at its lower end to the bracket 12 pivotally connected at 13 to the support 130.

On the bracket 12, there is mounted the cartridge 14 constituting the container for a supply of fluid mercury constituting in turn the conductor or electrical connection between the terminals 15 and 16 of the mercury switch formed thereby when the cartridge 14 is substantially horizontal as shown.

The terminal 15 in the present instance is connected by the conductor 17 to the outlet plug 18 connected to a suitable source of electric current, which plug 18 is in turn connected by the conductor 19 to one terminal of the winding of the electromagnet 20, the other terminal of which winding in turn is connected by the conductor 21 to the other terminal 16 of the mercury switch.

Reciprocably mounted in the coil of the electromagnet 20, there is provided the plunger or core 120 composed of soft iron or the like, the upper end of which is pivotally connected to the lever 22.

The electromagnet 20 in the present instance is preferably mounted upon the horizontal extension 23 of the bracket 24, the opposite faces of which are preferably engaged by cushioning members, such as the springs 25 and 26, the spring 25 being interposed between the upper face of the extension 23 and the abutment 27 and the spring 26 being interposed between the lower face of the extension 23 and the base forming face 28. 25 30

The bracket 24 has two upwardly extending arms 28 and 30, the upper end of the arm 30 forming a journal for the shaft 8, and the upper end of the arm 28 forming a journal for the pivot pin 31 pivotally connecting the lever 22 to such arm 28. The lever 22 has an extension 32, the outer end of which is connected by the spring 33 to the abutment 34 extending from the side of the arm 28.

The upper extension 35 of the lever 22 adjacent its pivot connection at the pin 31 is connected to one end of the brake band 36, the other end of which brake band is connected to the upward extension 37 of the arm 29. The brake band 36 constitutes a restraining member in the present instance to cooperate with another restraining member to arrest the movement of the tape puller, to wit the tape pulling roller 7 when the ticker comes to rest and the continued movement of the tape puller 7 increases the tension in the tape 4 to raise the link 11 and thereby rock the cartridge 16 to move the mercury fluid to interrupt the electrical connection between the ter- 50 45 55

minals 15 and 16 and thereby interrupt the electrical circuit of the electromagnet 20.

The second restraining member in the present instance is the brake drum 38 integral with the 5 tape pulling roller 7. When the electromagnet circuit is thus interrupted, the core 21 is released whereupon the spring 33 acts on the extension 32 in turn to clamp the brake band 36 into locking engagement with the brake drum 38 and 10 thereby anchor the tape pulling roller 7 against further movement with the shaft 8.

The shaft 8 in the present instance has fixed thereto the worm wheel 39 in mesh with the worm 40 fixed on the shaft 41 journaled in the casing 9 15 and having fixed on its outer end the sheave 42 connected to the sheave 43 on the motor shaft 44 of the motor 45 by the belt 46.

For normally connecting the pulling roller 7 in driving relation with the shaft 8, there is provided a slippage device, the disc 47 being pinned to the shaft 8 and having its face 48 constituting a clutch face maintained in engagement with the opposing face 49 of the drum 38. The roller 7 and drum 38 are yieldably maintained in engagement with the disc 47 by the pressure collar 50 splined to the shaft 8 to slide relative to, but rotate with, the shaft 8, the pressure collar 50 being urged into engagement with the roller 7 in turn to urge the drum 38 into engagement with the disc 47 by the spring 51 tensed between the abutment 52 and the pressure collar 50, the abutment 52 being preferably screw threadedly connected to the outer end of the shaft 8 to facilitate adjustment.

35 The tape 1 is preferably maintained in frictional driving engagement with the tape pulling roller 7 by the pressure roller 53 mounted at the end of the lever 54 journaled in the support 55. The end of the lever 54 is preferably connected 40 by a spring 56 or the like to yieldably press the roller 53 into frictional engagement with the tape 1.

In the embodiment shown in Fig. 4, the tape here designated 57 forms a twist between the 45 ticker 58 and the finger 59 of the electric switch distinguished from the embodiment shown in Fig. 1. In this embodiment, the finger 59 is mounted at the end of a lever 60 pivotally mounted in the switch box 61 to control a mercury switch similar to the mercury switch shown in Fig. 1 in turn to control the electric circuit of the electromagnet 62.

55 Here too, as distinguished from the embodiment shown in Fig. 1, the tape 57 after leaving the projector passes in a counterclockwise direction under the tape pulling roller 63 as distinguished from the embodiment shown in Fig. 1. From the tape puller 63, the tape 57 passes up to the rewind reel 64 journaled at the upper end 60 of the bracket 65 extending from the housing 66. The shaft of the rewind reel 64 has secured thereto a sheave 67 to receive the belt 68, preferably a spring belt, which is connected to a sheave mounted on the shaft 69 journaled in the housing 66.

In this embodiment there is also shown the screen 70 on which the images of the characters on the tape are projected by the projector 71, the light rays from the projector 71 passing up 70 through the tape 57 and then through the objective lens unit 72 onto the mirror 73 to be deflected onto the rear face of the translucent screen 70.

It is obvious that various changes and modifications may be made to the details of construc-

tion without departing from the general spirit of the invention as set forth in the appended claims.

I claim:

1. The combination with an intermittently operated tape feed, of a support, a tape puller 5 for drawing the tape across said support as it is fed thereto, a continuously operating electric motor independent of said tape feed, a driving member operatively connected to said motor, a driven member operatively connected to said tape puller, 10 said driving and driven members being operatively associated normally to drive with one another, a restraining means, a device engaging the tape and responsive to rock with varying tension in the tape, an electric circuit including an electromagnet and electric contacts, said electric contacts being movably associated with said device to close said electric circuit and energize said electromagnet, said electromagnet being operatively associated to control said restraining 20 means, said device being actuated by the tension in the tape resulting when the feed to said support is arrested and the tape puller continues its pull on the tape in turn to effect the movement of said contacts to open said electric circuit to 25 deenergize said electromagnet thereby to actuate said restraining means in turn to anchor said driven member against movement with said driving member.

2. The combination with an intermittently 30 operated tape feed, of a support, a tape puller for pulling the tape across said support as it is fed thereto, a continuously operating electric motor independent of said tape feed, a driving member operatively connected to said motor, 35 a driven member operatively connected to said tape puller, said driving and driven members being operatively associated normally to drive with one another, a restraining means operable to anchor and lock said driven member against 40 rotation, a movably mounted bracket, an electric switch including an element operatively associated with said bracket, said bracket being operatively connected to engage the tape and responsive to varying tension in the tape to be 45 rocked thereby in turn to open or close said switch, and an electric circuit including an electromagnet and said switch, said electromagnet being operatively associated to control said restraining means in turn to anchor said driven 50 member against movement with said driving member when the feed to said support is arrested and the tape puller continues its pull on the tape in turn to rock said bracket.

3. A tape pulling mechanism for converting 55 an intermittent tape feed to a continuous tape feed and operable to come to rest when the supply of tape thereto is interrupted comprising an intermittently operated tape feed, a support, a tape puller for continuously drawing the tape 60 across said support as it is delivered by said tape feed, a continuously operating electric motor independent of said tape feed, a driving member operatively connected to said motor, a driven member operatively connected to said tape puller, 65 said driving and driven members being operatively associated normally to drive with one another, a restraining member operable to anchor and lock said driven member against rotation when the tape feed stops and the tape 70 puller continues to operate to increase the tension in the tape between said tape feed and said tape puller, and a control mechanism for controlling said restraining member including a movably mounted bracket operatively connected 75

- to engage the tape and responsive to rock with varying tension in the tape, an electric circuit including an electromagnet and a switch operatively connected to said bracket, and a spring opposing said electromagnet to actuate said restraining member either to anchor or release said driven member, said electromagnet being energized when said switch is closed by the movement imparted to said bracket by the tape.
4. A tape pulling mechanism for converting an intermittent tape feed to a continuous tape feed and operable to come to rest when the supply of tape thereto is interrupted comprising an intermittently operated tape feed, a support, a tape puller for continuously drawing the tape across said support as it is delivered by said tape feed, a continuously operating electric motor independent of said tape feed, a driving member operatively connected to said motor, a driven member operatively connected to said tape puller, said driving and driven members being operatively associated normally to drive with one another, a restraining member operable to anchor and lock said driven member against rotation when the tape feed stops and the tape puller continues to operate to increase the tension in the tape between said tape feed and said tape puller, a movably mounted bracket operatively connected to engage the tape and responsive to varying tension in the tape, and a control including an electromagnet and a spring opposing one another and operatively connected to actuate said restraining member to anchor or release said driven member and an electric circuit for said electromagnet including a switch controlled by said bracket in turn to control the operation of said electromagnet.
5. A tape pulling mechanism for converting an intermittent tape feed to a continuous tape feed and operable to come to rest when the supply of tape thereto is interrupted comprising an intermittently operated tape feed, a support, a tape puller for continuously drawing the tape across said support as it is delivered by said tape feed, a continuously operating electric motor, a driving member operatively connected to said motor, a driven member operatively connected to said tape puller, said driving and driven members being operatively associated normally to drive with one another, a brake operable to anchor and lock said driven member against rotation when the tape feed stops and the tape puller continues to operate to increase the tension in the tape between said tape feed and said tape puller, a pivotally mounted bracket operatively connected to engage the tape and movable with the tape, and a control including an electromagnet and a spring opposing one another and operatively connected to actuate said brake to anchor or release said driven member and an electric circuit for said electromagnet including a switch controlled by said bracket in turn to control the operation of said electromagnet.
6. A tape pulling mechanism for converting an intermittent tape feed to a continuous tape feed and operable to come to rest when the supply of tape thereto is interrupted comprising an intermittently operated tape feed, a support, a tape puller for continuously drawing the tape across said support as it is delivered by said tape feed, a continuously operating electric motor independent of said tape feed, a driving member operatively connected to said motor, a driven member operatively connected to said tape puller, said driving and driven members being

operatively associated normally to drive with one another, a restraining member operable to anchor and lock said driven member against rotation when the tape feed stops and the tape puller continues to operate to increase the tension in the tape between said tape feed and said tape puller, a bracket operatively connected to engage the tape and movable with the tape, and a control including an electromagnet and a spring opposing one another operatively connected to actuate said restraining member to anchor or release said driven member and an electric circuit for said electromagnet including a switch operatively connected to said bracket, said switch being opened when said bracket is rocked by the tension resulting when the tape feed stops in turn to deenergize said electromagnet to enable said spring to actuate said restraining member to anchor said driven member and thereby said tape puller against further movement until the tension in the tape is again relieved with the operation of the tape feed.

7. A tape pulling mechanism for converting an intermittent tape feed to a continuous tape feed and operable to come to rest when the supply of tape thereto is interrupted comprising an intermittently operated tape feed, a support, a tape puller for continuously drawing the tape across said support as it is delivered by said tape feed, a continuously operating electric motor, a driving member operatively connected to said motor, a driven member operatively connected to said tape puller, said driving and driven members being operatively associated normally to drive with one another, a brake operable to anchor and lock said driven member against rotation when the tape feed stops and the tape puller continues to operate to increase the tension in the tape between said tape feed and said tape puller, a pivotally mounted bracket operatively connected to engage the tape and movable with the tape, and a control including an electromagnet and a spring opposing one another operatively connected to actuate said brake to anchor or release said driven member and an electric circuit for said electromagnet including a switch operatively connected to said bracket, said switch being opened when said bracket is rocked by the tension resulting when the tape feed stops in turn to deenergize said electromagnet to enable said spring to actuate said brake to anchor said driven member and thereby said tape puller against further movement until the tension in the tape is again relieved with the operation of the tape feed.

8. A tape pulling mechanism for converting an intermittent tape feed to a continuous tape feed and operable to come to rest when the supply of tape thereto is interrupted comprising an intermittently operated tape feed, a support, a tape puller for continuously pulling the tape across the support as it is delivered by said tape feed, a continuously operating electric motor, a driving member operatively connected to said motor and operatively associated normally to drive said tape puller, a brake operable to anchor and lock said tape puller against rotation when the tape feed stops and the tape puller continues to operate to increase the tension in the tape between said tape feed and said tape puller, a pivotally mounted bracket operatively connected to engage the tape and movable to be rocked by the tape, and a control including an electromagnet and a spring opposing one another operatively connected to actuate said

brake to anchor or release said tape puller and an electric circuit for said electromagnet including a switch controlled by said bracket in turn to control the operation of said electromagnet.

- 5 9. A tape pulling mechanism for converting an intermittent tape feed to a continuous tape feed and operable to come to rest when the supply of tape thereto is interrupted comprising an intermittently operated tape feed, a support, a tape puller for continuously pulling the tape across the support as it is discharged by the tape feed, and means for arresting the tape puller when the tape feed comes to rest including a brake drum associated with said tape puller, 10 a brake band operatively associated to anchor said brake drum and thereby said tape puller against rotation, a pivotally mounted bracket operatively connected to engage the tape and movable to be rocked by the tape, and a control including an electromagnet operatively connected to actuate said brake band to anchor or release said brake drum and an electric circuit for said electromagnet including a switch controlled by said bracket in turn to control the 15 operation of said electromagnet.

- 10 10. A tape pulling mechanism for converting an intermittent tape feed to a continuous tape feed and operable to come to rest when the supply of tape thereto is interrupted comprising an intermittently operated tape feed, a support, a tape puller for continuously pulling the tape across the support as it is discharged by the tape feed, means for arresting the tape puller when the tape feed comes to rest including a 15 brake drum associated with said tape puller, a brake band operatively associated to anchor said brake drum and thereby said tape puller against rotation, a pivotally mounted bracket operatively connected to engage the tape and movable to be rocked by the tape, and a control including an electromagnet and a spring opposing one another operatively to actuate said brake band to anchor or release said brake drum, an electric circuit for said electromagnet including 20 a mercury switch operatively connected to said

bracket, said switch being opened when said bracket is rocked by the tension resulting when the tape feed stops in turn to deenergize said electromagnet to enable said spring to actuate said brake band to anchor said brake drum and thereby said tape puller against further movement until the tension in the tape is again relieved with the operation of the tape feed. 5

11. A tape pulling mechanism operable to come to rest when the supply of tape thereto is interrupted comprising a tape puller, operated independent of the tape supply, restraining members one of which restraining members is operatively connected to rotate with said tape puller, a movably mounted bracket in engagement with the tape, an electric circuit including an electromagnet and an electric switch operatively associated with said bracket, said electro-magnet being operatively associated to the other of said restraining members when energized to actuate 10 said other restraining member to free said rotatable restraining member for rotation, said bracket when rocked by the tension in the tape resulting when the supply of tape to said tape puller is interrupted to actuate said electric switch in turn to deenergize said electro-magnet. 15

12. A tape pulling mechanism operable to come to rest when the supply of tape thereto is interrupted comprising a tape puller, a rotatable restraining member operatively connected to rotate 20 with said tape puller, a second restraining member, a pivotally mounted bracket in engagement with the tape and normally deflecting the tape, an electric circuit including an electro-magnet and an electric switch operatively associated 25 with said bracket, said electro-magnet being operatively associated to said second restraining member when energized to actuate said second restraining member to free said rotatable restraining member for rotation, said bracket when 30 rocked by the tension of the tape resulting when the supply of tape to said tape puller is interrupted to actuate said electric switch in turn to deenergize said electro-magnet. 35

AUGUST D. EITZEN. 45
